TELEPHONE SET FOR COMMUNICATION IN
AIRPLANES

Gerald Klein, Berlin-Lichterfelde, Germany, assignor to Siemens Apparate und Maschinen Gesellschaft mit beschränkter Haftung, Berlin, Germany, a corporation of Germany

Application June 26, 1937, Serial No. 150,429
In Germany June 27, 1936

3 Claims. (Cl. 179—156)

My invention relates to telephone sets for communication in airplanes, and more particularly to a casing for receivers adapted to be used in connection with aviators' helmets and is directed generically to the same subject matter as is disclosed in the copending application of Karl Wenzky, Serial No. 163,077, filed September 9, 1937.

The object of my invention is to provide a casing for the receiver simple to manufacture, light in weight and which will exclude all outside noises so as to permit a clear signal reception by the aviator. To this end, the casing and the bearing points for securing the constituent elements of the telephone receiver are made of one piece having the form of a shell and surrounding the ear of the user. The casing must therefore be of solid material and is preferably made of a light metal so as not to considerably increase the weight of the aviator's helmet or the like while at the same time upon a reduction of air pressure it properly seals the ear so as to exclude any noises which might interfere with a clear understanding. The advantage of such an arrangement is also the saving in weight by the omission of the customary prior art separate receiver casing.

The casing is preferably given an oval or round shape in order to adapt it comfortably to the ear. Within the casing in the central portion thereof is provided a circular threaded flange which receives the several constituent elements of the telephone mechanism. The telephone mechanism is firmly secured within the casing by screws or the like, a socket supporting the diaphragm and the cover of the telephone engaging the threaded flange. The casing is secured to the aviator's helmet or the like by means of a spring ring placed in the casing and fastened to the material of the helmet, the helmet lining consisting, for instance, of lamb skin or the like resiliently covering the open inner side of the casing and being provided at this point with openings for the passage of the sound in order to attain a clear understanding with the smallest possible pressure.

In the accompanying drawing is shown an embodiment of my invention in diagrammatic form.

Fig. 1 shows a vertical sectional view of the receiver embodying my invention in connection with an aviator's helmet shown in part and in section.

Fig. 2 shows the inner view of the casing according to the invention with the telephone sys-

tem, the diaphragm and the cover being removed.

The casing 1 which preferably has the shape as shown in Figs. 1 and 2 is provided in its central portion with a flat pad 1a, surrounded by a circular flange 2 which together with pad 1a and the casing forms one single piece, preferably an aluminum die casting. The telephone magnet system 3 which in this case is of the two-coil type is supported on pad 1a within the circular flange 2 and is secured to the casing 1 by screws 15. The laterally projecting parts of the magnet system 3 are provided with plug connections 4 which pass through openings 16 arranged in the flange 2. Onto the end of flange 2 is threaded the ring 7 which serves as a support for the diaphragm 5 and by which it is positioned over or in front of the magnet system 3. A centrally perforated cover 6 holds the diaphragm to ring 7. The position of the ring 7 is set by a locking ring 8, also threaded onto flange 2, in order to 20 secure the desired distance between the diaphragm 5 and the pole pieces of the magnet system. To secure the telephone leads of the helmet leading to the telephone each end of the magnet system 3 is provided in the neighborhood of the plug connections 4 with a terminal 9 also supported by casing 1, and to which the leads extending to the helmet are connected.

The rim 17 of casing 1 is slightly inwardly upset as shown in Fig. 1, so that it can be firmly 30 secured to the aviator's helmet 10 by means of a spring ring 11 which is fastened to the leather cover 12 of the helmet 10, and over which the casing, also covered with leather or the like, is slipped as shown in Fig. 1. To reduce the pressure of the edge of the casing against the portion of the head adjacent to the user's ear and to attain at the same time a proper sealing of the opening of the casing, the opening of the latter is covered by the helmet lining 13 consisting, for instance, of lamb skin which forms an elastic pad between the ear and the casing (as shown by the dash lines in Fig. 1) and is provided with openings 14 for the passage of the sound. In this manner a casing for telephones 40 is provided which is particularly useful for aviator's helmets, of simple construction, light in weight, easily to be secured to the helmet and which will exclude all outside noises.

I claim as my invention:

1. A detachable telephone receiver in particular for aviators' helmets or the like, comprising a shell-shaped casing of solid material, fashioned to circumscribe the ear of the user and having in its central interior portion a supporting pad 50 55

- and an annular wall surrounding said pad, both integral with the casing wall and shaped to support individually the several constituent elements of the receiver mechanism in operative relation to one another, and a spring ring on the helmet for supporting said casing at its rim, the wall of the helmet having a yielding portion covering the inside of said casing and being provided with perforations for transmitting the sound to the ear of the user.
2. In combination, an aviator's helmet having an opening therein, and a telephone receiver casing attached to said helmet exteriorly thereof and acoustically sealing said opening, said casing being fashioned to circumscribe the ear of the

user and comprising means integral therewith for mounting the operative parts of said receiver directly to said casing.

3. In combination, an aviator's helmet, having an opening therein, a casing attached to said helmet and exteriorly thereof and acoustically sealing said opening, said casing being fashioned to circumscribe the ear of the user and comprising a base integral with said casing, an annular wall surrounding said base and integral therewith, and operative elements of a telephone receiver attached directly to said base and wall, respectively.

GERALD KLEIN. 15
